UNITED STATES PATENT OFFICE.

CHARLES BERGHOEFER, OF MILWAUKEE, WISCONSIN.

HOISTING DEVICE.

SPECIFICATION forming part of Letters Patent No. 635,643, dated October 24, 1899.

Application filed March 29, 1899. Serial No. 710,865. (No model.)

To all whom it may concern:

Be it known that I, CHARLES BERGHOEFER, a citizen of the United States, and a resident of Milwaukee, in the county of Milwaukee, and State of Wisconsin, have invented certain new and useful Improvements in Hoisting Devices; and I do hereby declare that the following is a full, clear, and exact description thereof.

10 My invention has especial reference to that class of hoisting devices which employ what is commonly known as "clam-shell" buckets; and it consists in certain peculiarities of construction and combination of parts, as will be 15 fully set forth hereinafter and subsequently claimed.

In the drawings, Figure 1 is a front elevation of my device, partly broken away to better illustrate certain details of construction, 20 showing a pair of buckets in their closed position for being elevated. Fig. 2 is a vertical sectional view on the line 2 2 of Fig. 1. Fig. 3 is a detail under side view of the parts shown above the line 3 3 in Fig. 1, omitting 25 the power-cables. Fig. 4 is a perspective view of the worm-gear-supporting frame.

Referring to the drawings, A A' represent a pair of clam-shell buckets open at the top and inner adjacent sides and with closed curved 30 bottoms.

B represents the worm - gear - supporting frame, (shown detached in Fig. 4,) comprising two U-shaped end pieces b b, united by upper longitudinal beams c c, having transverse seats or bearings d d on their upper 35 surfaces for the journals e e of the worm-wheels C C' and drums D D', said journals being held in place by caps f f and suitable bolts, as shown, and the end pieces b b having 40 bearings g g for the worm-shaft E, which latter is provided with proper right and left handed threads F G for engagement with the described worm-wheels C C' and with a central pulley H.

45 I I represent a pair of angular straps extending from the worm-shaft E to studs a on the bucket A, and I' I' a like pair of said straps extending from said shaft to studs a' on the bucket A'.

50 J J represent the long arms, and j j the short upper arms, of a pair of bell-crank links pivotally suspended from a shaft or journal K,

and J' J' represent the long arms, and j' j' the short upper arms, of a corresponding pair of links, also pivotally suspended from said 55 shaft K, the lower ends of the long arms J J being pivoted on the described studs a of bucket A and the corresponding ends of the arms J' J' being pivoted on the studs a' of bucket A'. The outer ends of the short arms 60 j j are connected together by a brace L and just inside that by a journal M, carrying an idler-pulley m, and similarly the outer ends of the short arms j' j' are connected together by a brace L' and just inside that by a journal M', carrying an idler - pulley m'. The shaft K is centrally provided with a hoisting-pulley O, and the same shaft carries two 65 hangers N N', and from the hanger N ropes, chains, or cables n n run to the drum D on 70 each side of the worm-wheel C, while from the hanger N' similar ropes, chains, or cables n' n' run to the drum D' on each side of the worm-wheel C'. In the illustration given the ropes n and n' are connected to the hangers 75 N and N' by means of intermediate rings p and p', passing through holes in said hangers, but this is immaterial.

P P represent the hoisting-cable passing around the hoisting-pulley O, and Q Q the 80 cable that passes around the pulley H on the worm-shaft E to revolve said shaft in either direction, as required, these cables P and Q running to proper engines or other sources of power, (not shown,) and the cable Q travels 85 in the grooves of the idler-pulleys m m', between the same and the braces L L', which latter are preferably in the form of rollers, as shown, to keep the said cable within the said grooved idlers and also to lessen friction. Of 90 course the cables P Q may be ropes or chains, just as preferred.

The operation of my invention will be readily understood from the foregoing description of its construction taken in connection with 95 the accompanying drawings. In Figs. 1 and 2 the buckets A A' are shown closed and the ropes n n' are fully wound up upon the drums D D', the worm-gear in this position keeping the buckets closed. In order to permit the 100 buckets A A' to open and separate, the worm-shaft E is revolved by means of the cable Q in the direction of the arrows, the worms G and F on said shaft thereby turning the worm-

wheels C C' in the direction shown by the arrows and allowing the ropes n n' to unwind from the drums D D', whereupon the said buckets A A' will separate and drop by gravity, opening out to their fullest extent and dumping their contents. In this condition the whole device can be lowered by means of the cable P, and when the open buckets reach the mass of material to be elevated the said buckets are in the position of scoops or shovels, and an operation of the power-cable Q in the reverse direction will revolve the worm-shaft E and the worm-wheels C C' in the reverse directions to those indicated by said arrows, thereby closing said buckets together again in their former position (shown in the drawings with the scooped-up material safely held thereby) and winding up the ropes n n' upon the drums D D', and then the cable P is operated to raise the load ready for dumping, as before described.

Having thus described my invention, what I claim as new, and desire to secure by Letters Patent, is—

1. In a hoisting device, the combination with a pair of buckets, open at their top and adjacent inner sides, of a hoisting-pulley and its journal; a pivotal link connection between said journal and said buckets; a worm-gear-supporting frame, carrying a worm-shaft, and pair of worm-wheels; a pivotal strap connection between said worm-shaft and said buckets; a power-pulley on the worm-shaft; wind-

ing-drums on the worm-wheel shafts; and hangers suspended from the hoisting-pulley journal, and connected by cords, chains or cables to said drums. 35

2. In a hoisting device, the combination with a pair of buckets, open at their top and inner-adjacent sides, of a worm-gear-supporting frame, a worm-shaft and a pair of worm-wheels journaled therein; a pair of drums on each worm-wheel journal; a pair of straps pivotally connecting each end of the worm-shaft with the outer upper angle of each 40 bucket; an upper shaft or journal; a pair of links suspended from each end of said upper journal and pivotally connected to the outer upper angles of the said buckets; a hoisting-pulley on said upper journal; a power-pulley 45 on the worm-shaft; a pair of hangers on said upper journal, one on each side of the hoisting-pulley; a pair of cords, chains or cables connecting each hanger with the drums on the adjacent worm-wheel journal; a power-cable 50 on the power-pulley; and a hoisting-cable on the hoisting-pulley. 55

In testimony that I claim the foregoing I have hereunto set my hand, at Milwaukee, in the county of Milwaukee and State of Wisconsin, in the presence of two witnesses. 60

CHARLES BERGHOEFER.

Witnesses:

H. G. UNDERWOOD,
B. C. ROLOFF.
